(57) **CLAIM**

The ornamental design for a dual-mode internet phone kit, as shown and described.

DESCRIPTION

FIG. 1 is a front view of a telephone cradle for a dual-mode internet phone kit showing our new design;

FIG. 2 is a side view thereof;

FIG. 3 is a front view of the cradle of FIG. 1;

FIG. 4 is a side view of the cradle;

FIG. 5 is a back view of the cradle;

FIG. 6 is a top view of the cradle; and,

FIG. 7 is a perspective view of the cradle.

The broken lines in FIGS. 1-2 are included for the purpose of illustrating a portion of the phone that forms no part of the claimed design.
